(57) **CLAIM**

We claim the ornamental design for a battery vent adapter, as shown and described.

DESCRIPTION

FIG. 1 is a perspective view of a battery vent adapter showing our new design;

FIG. 2 is a top plan view thereof, the bottom plan view being a mirror image;

FIG. 3 is a right side view thereof, the left side view being a mirror image;

FIG. 4 is a front elevation view thereof; and,

FIG. 5 is a back elevation view thereof.

The subject matter shown in broken lines in the drawings constituting environment only and forming no part of the protection claimed.
